(57) **CLAIM**

The ornamental design for a digital camera body of lens
replacing type, as shown and described.

DESCRIPTION

FIG. 1 is a front, top and right side perspective view of a
digital camera body of lens replacing type showing my new
design;

FIG. 2 is a rear, top and left side perspective view thereof;
FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines shown in the drawings depict portions of
the digital camera body of lens replacing type that form no
part of the claimed design.

1 Claim, 5 Drawing Sheets
